UNITED STATES PATENT OFFICE

DANIEL F. SEREMBA, OF JERSEY CITY, NEW JERSEY

SHOE

Application filed November 7, 1930. Serial No. 493,981.

The invention aims to provide an improved shoe specially designed for baseball players and in running generally. It serves to protect the arch of the wearer's foot, serving as a prophylactic against injury to the arches. It serves also to prevent slipping and to enable the wearer to get a quick start from a standing position.

The accompanying drawings illustrate an embodiment of the invention.

Fig. 1 is a longitudinal section of a shoe with the outline of a foot and the location of the principal bones therein;

Fig. 2 is an underside plan view of the shoe;

Figs. 3, 4 and 5 are elevations showing different positions.

The shoe may be of any style. In the case illustrated it has an upper 1, on the bottom 20 of which is an inner sole 2 and an outer front sole 3 which extends back under the first metatarsal bones 4. Back of the metatarsal bones are the bones forming the key portion of the arch, the internal cuneiform 25 bone 5 and the scaphoid bone 6. Back of this is the astragalus 7, the tibia 8 and the os calcis or heel 9. It is common to provide a heel plate on shoes under the rear portion 30 of the foot, leaving between it and the front sole 3 a length of about three inches of the inner sole 2 for flexibility. Such a heel plate, for example, would extend in the ordinary shoe to about the point indicated by the dotted line 10.

35 I propose to provide a rear plate 11 which extends from the rear end of the shoe forward to a greater length than usual so as to bring it under the key of the arch formed by the bones 5 and 6. In an ordinary shoe, 40 say about eleven inches in total length, this rear plate would be about five and one-half inches long along the inside edge (the left edge of the right foot, or the right edge of the left foot), and an inch shorter at the 45 outer side.

This plate is of stiff leather similar to that commonly used for heel plates. It may be of one or more plies and may be reinforced with a metal plate for greater stiffness and 50 support under the key point of the arch.

The front sole plate and the rear plate are provided with cleats to give the runner a hold on the turf to prevent slipping. On the front sole plate there is shown a fixture consisting of three cleats 12 and 13 respectively 55 connected to each other by thin webs 14 and riveted to the sole. This is a common form of cleat. The cleat 12 is substantially transverse to the length of the shoe and the cleats 13 oblique and approximately longitudinal. 60

The rear plate or sole 11 is provided with a cleat 15 at the rear which extends transversely, cleats 16 at the sides which extend obliquely longitudinally and a cleat 17 which is transverse or approximately so; these being connected by a web 18 and fastened by rivets to the sole.

The web 14 which holds the front cleats extends from each cleat to the other two, making a closed figure. The web 18, however, is an open figure extending from the outside cleat 16 rearwardly and thence forwardly along the inside edge of the sole to the end carrying the cleat 17. The web 18, therefore, has substantially no greater 75 weight than the web of the front cleats although it carries one more cleat than the front web.

In the standing position, say of a fielder in a baseball game, practically all of the cleats 80 will bear on the ground as in Fig. 3. The arch will, therefore, be supported at its center and there will be no substantial strain on the foot. When the wearer starts to run he will 85 dig the rear cleat 15 into the earth and if he is going to move sidewise he will dig in with one or the other of the side cleats 16, according to the direction of his movement.

As he advances, the middle cleat 17 will 90 dig into the earth and will provide him with a continued point of reaction to propel himself forward, at the same time supporting the arch of his foot from excessive bending downward. This position is shown in Fig. 4. In his further movement, his grip on the earth will depend first on the longitudinal front cleats 13 and finally on the transverse front cleat 12, as in Fig. 5.

In baseball shoes of the previous type commonly used there have been no transverse 100

cleats between those at the extreme rear end and the extreme front end respectively. In the intermediate position, therefore, the runner has no substantial grip on the earth helping to propel him forward. This has occasionally caused slipping. And in any case it causes an excessive bending of the foot and frequent injury to the arch in the course of time.

10 The approximately central cleat 17 provided by this invention gives the wearer a good grip for forward propulsion in practically every position and tends to prevent injury to the arches by avoiding the necessity of bending the foot excessively to grip with the toe cleat.

15 The shoe illustrated lacks the comparatively high heel which is used in the common walking shoe. Running shoes are made usually without such heels so as to avoid the concentration of weight on the toe and to secure a distribution of the weight and the reaction over the full length of the sole.

20 The heel plate 11 is of the same order of thickness as the front sole plate 3. With this style of shoe the present invention is particularly useful. With running shoes of this style having cleats only at the toe and heel ends, there is a considerable strain on the 25 muscles and tendons which extend from the toe bones to the heel bone and form a sort of tension cord of the arch formed by the bones.

30 In running or starting quickly, a transfer of the point of reaction from the heel end clear to the toe end puts a strain on such muscles and tendons which if repeated for a considerable season causes them to slip to a certain extent and permit the fall of the arch. 35 But by introducing an intermediate point of reaction as by the middle cleat 17, the weight or reaction is not transferred at one movement from heel to toe but is transferred gradually so that there is not the sudden strain 40 on the muscles and tendons referred to and they will be prevented from yielding or slipping to a very substantial extent and will be kept in normal condition for a longer period of time.

45 50 Various modifications of the invention may be made by those skilled in the art without departing from the invention as defined in the following claims.

55 1. A running shoe having transverse cleats at the rear and front ends and having an intermediate transversely extending cleat stiffly connected to the rear end cleat and adapted to grip the earth in an intermediate position between that of starting on the heel 60 and going forward on the toe.

65 2. A running shoe having transverse cleats at the rear and front ends and having an intermediate transversely extending cleat under the shank portion of the sole and adapted to grip the earth in an intermediate

position between that of starting on the heel and going forward on the toe.

3. A running shoe having comparatively stiff front and rear sole portions with an intermediate comparatively flexible portion and having transverse cleats at the rear and front ends and having an intermediate transversely extending cleat adapted to grip the earth in an intermediate position between that of starting on the heel and going forward on the toe, said intermediate cleat being on the inner side of the sole of the shoe.

4. A running shoe having toe cleats and a heel fixture having the following cleats, 80 namely, a transverse one at the rear, longitudinally extending ones at opposite sides and, in advance of these, a transversely extending cleat.

5. A running shoe having toe cleats and heel cleats, said heel cleats including a transverse one at the rear, longitudinally extending ones at opposite sides and, in advance of these, a transversely extending cleat and a web extending from one side cleat in succession to the rear cleat, the opposite side cleat and the forward cleat and open between the first side cleat and the forward cleat.

6. A running shoe having a front sole plate and a rear heel plate of approximately the same thickness and having a more flexible sole between said plates and having transverse cleats at the rear and front ends of said plates respectively and having an intermediate transversely extending cleat at the front of the rear plate.

7. A running shoe having a front sole plate and a rear heel plate of approximately the same thickness and having a more flexible sole between said plates and having transverse cleats at the rear and front ends of said plates respectively and having an intermediate transversely extending cleat at the front of the rear plate and having longitudinally extending cleats at the sides.

In witness whereof, I have hereunto signed my name.

DANIEL F. SEREMBA.
